[57] CLAIM

The ornamental design for a wooden faux book spine for furniture ornamentation, as shown and described.

DESCRIPTION

FIG. 1 is a front elevation view of a wooden faux book spine for furniture ornamentation showing my new design;

FIG. 2 is a perspective view thereof;

FIG. 3 is a side view thereof; and,

FIG. 4 is a top view thereof.

The bottom and rear views of the design are not shown and form no part of the claimed design.
